DESIGN FOR A COMBINATION MATCH FOLDER AND ARTICLE HOLDER

Joseph B. Waller, Baltimore, Md.

Application May 18, 1938, Serial No. 77,269

Term of patent 14 years

To all whom it may concern:

Be it known that I, Joseph B. Waller, a citizen of the United States, residing at Baltimore (independent city), State of Maryland, have invented a new, original, and ornamental Design for a Combination Match Folder and Article Holder, of which the following is a specification, reference being had to the accompanying drawing, forming part thereof, in which:

bination match folder and article holder, showing my new design.

I claim:

The ornamental design for a combination match folder and article holder, as shown.

JOSEPH B. WALLER.
